UNITED STATES PATENT OFFICE

155,052

DESIGN FOR A CLOTHESPIN

Jesse Wallen, Prestonsburg, Ky.

Application July 16, 1948, Serial No. 147,620

Term of patent 7 years

(Cl. D17—6)

To all whom it may concern:

Be it known that I, Jesse Wallen, a citizen of the United States, residing at Prestonsburg, in the county of Floyd and State of Kentucky, have invented a new, original, and ornamental Design for a Clothespin, of which the following is a specification, reference being had to the accompanying drawings, forming a part thereof.

I claim:

The ornamental design for a clothespin, as shown.

JESSE WALLEN.
